UNITED STATES PATENT OFFICE

163,808

VEHICLE TRAILER BODY

John B. King and Eugene Chosy, Delphos, Ohio,
assignors to Gramm Trailer Corporation, Del-
phos, Ohio, a corporation of Ohio

Application April 4, 1950, Serial No. 8,974

Term of patent 14 years

(Cl. D14—3)

To all whom it may concern:

Be it known that we, John B. King, a citizen of the United States and a resident of Delphos, Ohio, and Eugene Chosy, a citizen of the United States and a resident of Delphos, Ohio, have invented a new, original, and ornamental Design for a Vehicle Trailer Body, of which the following is a specification, reference being had to the accompanying drawing, forming a part thereof.

In the drawing:

Figure 1 is a rear perspective view of the vehicle trailer body showing our new design;

Figure 2 is a front perspective view of the vehicle trailer body, and

Figure 3 is a top plan view of the vehicle trailer body.

We claim:

The ornamental design for a vehicle trailer body, as shown.

JOHN B. KING.
EUGENE CHOSY.
